UNITED STATES PATENT OFFICE.

WENONAH BLACKWELL, OF SEATTLE, WASHINGTON.

TOY DOLL.

Application filed April 13, 1925. Serial No. 22,861.

This invention relates to an improved toy doll and has for its object to provide an improved toy device of this kind of a simple, inexpensive nature, and that will have a pleasing attractive appearance.

Another object of the invention is to provide for the use of a handkerchief, as ordinarily designed, to form part of the doll without in any way destroying or affecting the handkerchief for use as a handkerchief when not employed as part of the doll.

A further object of the invention is to provide for the use of a handkerchief or similar piece of fabric or material to form part of the doll, and to provide for the ready interchanging of handkerchiefs or like pieces of material of varying color and ornamentation whereby amusement is afforded and a great variety of combinations and effects is made possible.

The invention, with other objects and advantages thereof, and the particular construction, combinations and arrangements of parts comprising the same will be understood from the hereinafter contained detail description, when considered in connection with the accompanying drawings, forming part hereof, and illustrating two embodiments of the invention.

In the drawings:

Figure 1 is a front elevation of a toy doll constructed in accordance with the present invention.

Fig. 2 is a central longitudinal section.

Fig. 3 is a front elevation of the doll structure without the removable dress member.

Fig. 4 is a detail plan view, on a reduced scale, of a handkerchief adapted to form part of the doll.

Fig. 5 is a front elevation of a modified construction.

Fig. 6 is a detail front elevation of the upper body member of the modified construction illustrated in Figure 5.

Fig. 7 is a longitudinal section on the line 7—7 Figure 6.

Fig. 8 is a central longitudinal section of the modified construction illustrated in Figure 5.

Fig. 9 is a detail section on the line 9—9 Figure 3.

The invention comprehends a toy doll comprising an upper figure or body member including head, shoulder and arm portions, and a handkerchief or like pieces of fabric or material, with means for detachably engaging the handkerchief or similar pieces of material with the upper body member to suspend the same therefrom to constitute a lower part or dress member of the doll. More particularly the invention contemplates a figure or body member provided with a loop portion adapted to have a handkerchief or the like draped therethrough and to hold the same suspended from the upper body member in two folds.

While specific embodiments of the invention are illustrated in the drawings, it will of course be understood that changes and variations in the particular construction shown, and the carrying out of the invention in other forms, as will appeal to those skilled in the art and falling within the scope of the appended claims may be practiced without departing from the spirit of the invention.

Referring to a detail description of the particular embodiment of the invention illustrated in Figures 1 to 4 of the drawings, the particular construction shown comprises an upper body member 1 including head 2, shoulders 3, and arm portions 4. The upper body member 1 is provided with a loop portion 5 adapted to be detachably engaged by and to hold a handkerchief 6 or the like suspended from the upper body portion 1 to constitute a lower part or dress member of the doll, the handkerchief 6 or similar piece of fabric or cloth being draped or threaded through the loop portion 5 to hang in two folds and gathered in or confined at the line of fold as illustrated in Figure 1 of the drawings. In this instance, the loop portion 5 is formed by providing the upper body member with a transverse slot 5^a, said slot being shown located at the lower part of the upper body member 1 between the arm portions 4. A pin 7 or equivalent means may be and

preferably is employed to secure the folds of the handkerchief 6 or the like together at a point beneath the loop portion 5. The pin 7 may be applied, as shown, so that while securing the folds together it is concealed from view.

8 designates leg and foot portions connected to the upper body member 1 by loops 9 of tape or the equivalent, engaging around the lower part 5^b of the loop portion 5.

10 designates a loop of ribbon, cord or the like engaged with an eye 11 at the top of the upper body member 1 by which the doll may be hung up or carried.

15 The upper body member 1 and leg and foot portions 8 may be constructed from any suitable material. These parts may be formed from celluloid, papier mâché, or cut from cardboard or wood as in the construction shown.

20 The head portion 2 of the upper body member 1 is painted or otherwise decorated with the representation of a head, and the shoulder and arm portions 3, 4, as illustrated, have produced thereupon by painting or in any other suitable way, the representation of an upper part of a dress.

25 The modified construction illustrated in Figures 5 to 8 of the drawings, comprises an upper body member 12, this being substantially the same in construction as the corresponding upper body member 1 of the form of the device illustrated in Figures 1 to 3 of the drawings except that in this instance the body member 12 is provided with a loop portion 13 consisting of a strip of elastic secured at its ends to the body member 12 at its lower edge 12^a by tracks 14 or equivalent fastening means. 15 designates a handkerchief, which in this instance is folded diagonally and then passed through the loop portion 13, as shown, to hang in two folds, which are secured together by a pin 16.

30 It will be noted that the particular construction hereinbefore described is composed of few parts, is of an inexpensive nature and possesses a pleasing attractive appearance. The invention provides for the utilization of handkerchiefs as ordinarily made, to form 35 part of the doll without in any way marring or affecting the same for their intended purpose. Handkerchiefs and similar pieces of cloth of various kinds, colors, and ornamentation may be employed, so that a wide range 40 of combinations and different effects can be easily produced, the upper dress part produced on the shoulder and arm portions of the upper body member may be of any color desired, and the handkerchief or like 45 pieces of material employed may be of a similar or contrasting color. The application of the handkerchief or like piece of material can be quickly effected, and as will be appreciated the ready attachment or interchanging of handkerchiefs or like pieces

50 of material of different kinds adds to the amusement afforded by the doll.

What I claim is:

55 1. A toy doll comprising an upper body member including a head, shoulder and arm portions, a piece of fabric adapted to be suspended from the upper body member to constitute a lower dress member, said upper body member having a transverse loop portion at its lower part adapted to have the 70 piece of fabric draped therethrough and to hold the same suspended in two folds below and free of the body member.

60 2. A toy doll comprising an upper body member including head, shoulder and arm 80 portions, and a handkerchief or the like, said upper body member being provided with a transverse loop portion at its lower part adapted to have the handkerchief draped therethrough and to hold the same suspended in two folds below and free of 85 said body member to constitute a lower dress member.

65 3. A toy doll comprising an upper body member including head, shoulder and arm 90 portions, and a handkerchief or the like, said upper body member being provided with a transverse loop portion at its lower part adapted to have the handkerchief draped 95 therethrough and to hold the same suspended below the body member and gathered at the line of fold to constitute a lower dress member.

70 4. A toy doll comprising an upper body member including head, shoulder and arm 100 portions, and a handkerchief or the like, said upper body member being provided with a loop portion at its lower part adapted to have the handkerchief draped therethrough and to hold the same suspended in two folds 105 below the body member to constitute a lower dress member, and means for securing the two folds of the handkerchief together at a point below said loop portion.

75 5. A toy doll comprising an upper body 110 member including head, shoulder and arm portions, and a handkerchief or the like, said body member being provided with a transverse slot at its lower part forming a loop portion adapted to have the handkerchief draped therethrough and to hold the same suspended in two folds below and free of the body member to constitute a lower dress member.

80 6. A toy doll comprising an upper body 120 member including head, shoulder and arm portions, a piece of fabric adapted to be suspended from the upper body member to form a continuation thereof and constitute a lower dress member, said upper body member having a loop portion at its lower part adapted to have the piece of fabric draped therethrough and to form a support 125 for the same, leg and feet portions, and means engaging over said loop portion and 130

connecting the leg and feet portions to the upper body member.

7. A toy doll comprising an upper body member including head, shoulder and downwardly extending arm portions, and a handkerchief or the like, said body member being provided with a transverse loop at its lower part between said arm portions

adapted to have the handkerchief draped therethrough and to hold the same suspended in two folds below and free of the body member to constitute a lower dress member. 10

In testimony whereof I hereunto affix my signature.

WENONAH BLACKWELL.
